(57) **CLAIM**

The ornamental design for a reclosable box, as shown and described.

DESCRIPTION

FIG. 1 is a top, front, right side perspective view of a reclosable box showing my new design in a fully closed state;

FIG. 2 is a front elevation view thereof;

FIG. 3 is a rear elevation view thereof;

FIG. 4 is a right side elevation view, the left side elevation view being a mirror image thereof;

FIG. 5 is a top plan view thereof;

FIG. 6 is a bottom view thereof;

FIG. 7 is a top, front, right-side perspective view thereof, in a fully open state;

FIG. 8 is a front elevation view thereof;

FIG. 9 is a rear elevation view thereof;

FIG. 10 is a right-side elevation view thereof, the left side elevation view being a mirror image of the right-side elevation view;

FIG. 11 is a top plan view thereof;

FIG. 12 is a bottom view thereof;

FIG. 13 is a top, front, right-side perspective view thereof, in a partially open state; and,

FIG. 14 is a top, front, right-side perspective view thereof, in a condition of use.

The broken lines showing content within the reclosable box illustrate environmental structure and form no part of the claimed design.

1 Claim, 11 Drawing Sheets
